MOULDBOARD OR BREAST OF PLOW

Shinjiro Takakita, Shoichi Takakita, Minoru Takakita, Tsutomu Takakita, and Akira Takakita, Nabari-Cho, Nakagun, Mieken, Japan

Original application August 15, 1952, Serial No. 304,662, now Patent No. 2,785,617, dated March 19, 1957. Divided and this application January 11, 1957, Serial No. 633,702

4 Claims. (Cl. 97—123)

This invention relates to plows and more specifically to the mouldboards or, as they are sometimes designated, the breasts thereof, and this application is a division of our application for United States Letters Patent Serial No. 304,662, filed August 15, 1952, and now Patent Number 2,785,617.

An important object of the invention is to provide a skeleton mouldboard which may be adjusted as a unit with respect to a plowshare and plow frame, and also the individual ribs of the mouldboard adjusted with respect to the plowshare and frame, so as to expedite and improve plowing operations.

Another important object of the invention is to provide a mouldboard including a plurality of spaced-apart ribs which ribs may be warped or twisted to assume selected positions with respect to the plow frame and share so that the soil will be more readily lifted, turned, sheared and pulverized than in the case of rigid skeleton ribs of skeleton mouldboards and, consequently, the amount of labor reduced in plowing.

Still another important object of the invention is to provide angularity adjusting means for the mouldboard which provides for such means disposed well inwardly of the edges of the mouldboard and for ready manipulation of a pin to effect adjustment in conjunction with an elongated opening with converging walls. This has been found a very desirable non-rigid construction and tends to prevent breakage of the ribs.

Other objects and advantages of the invention will be apparent during the course of the following detailed description of the invention, taken in connection with the accompanying drawing, forming a part of this disclosure and in which drawing:

Fig. 1 is an elevation of a plow, with the mouldboard in vertical section.

Fig. 2 is a rear elevation of the mouldboard of Fig. 1 removed from the plow frame, with portions of the structure in section.

Fig. 3 is an elevation of portions of angularity adjusting means of the mouldboard of Figs. 1 and 2.

Fig. 4 is an elevation of a part of the angularity adjusting means of Fig. 3.

In the drawing, wherein for the purpose of illustration is shown a preferred embodiment of the invention and wherein similar reference characters designate corresponding parts throughout the several views, the letter A designates a frame of a plow; B, a plowshare; C, the adjustable mouldboard of this application; D, a support means for the mouldboard; and E, means to rock the plowshare B and mouldboard C.

The frame A may be of conventional construction and includes a body portion 5, handle portion 6 at the upper end of the body portion, and landside 7 at the lower end of the body portion and extending forwardly therefrom.

At the forward end of the landside 7 is the plowshare or, as it is more commonly called, share B, having a point body portion 10 and an upwardly and rearwardly inclined shimpiece 11, providing a first support means for

2

the mouldboard C and which share is movably carried by the landside for controlled limited rotation upon a forwardly and rearwardly extending horizontal axis, as is well known in the art.

5 The adjustable mouldboard C, being of skeleton form, includes a plurality of spaced-apart, elongated, upwardly and rearwardly inclined, bowed ribs 15, which are longitudinally twistable. Each rib has an elongated, narrow body portion 16, with upper and lower faces, a lowermost downturned flange 17, substantially parallel, downwardly-extending side flanges 18, and an uppermost rearwardly-extending flange 19, which may be narrower than the flange 17. The material of the ribs 15 is such that the ribs may be twisted or partly canted or warped. Spring steel is a well-known material having the necessary characteristic. Preferably, as shown in Fig. 2, the ribs vary in length so as to provide an upwardly curved upper edge profile for the mouldboard as a whole, and are normally in substantially the same inclined plane.

10 20 Preferably, adjacent the upper ends of the ribs 15, they are joined together by connection means 20 which is shown as an elongated bracket body portion 21 which may be a substantially flat strip, as of steel, extending with its longitudinal axis normal to the longitudinal axes of the ribs, and provided with a plurality of feet or lugs 22, one for each rib, rigid with the portion 21 and extending, in parallelism, normal thereto, from a longitudinal edge thereof. The feet or lugs may be secured rigidly to the ribs in any approved way, such as by conventional rivets 23. At substantially the center of the portion 21 is a pivot opening 24 for a pivot member 31 to be subsequently described.

15 25 30 35 40 45

First support means 25 for and constituting a part of the mouldboard C, includes an elongated support or bracket body 26, secured to the upper end portion of the shimpiece 11 in any approved way, such as by conventional welding for rotative movement therewith, and having a downwardly inclined elongated flange 27 at its upper end. Projecting upwardly in substantial parallelism from the flange 27 are a plurality of spaced-apart pivot pins 28, one for each rib 15, since their upper end portions extend through suitable pivot openings in the central portions of the flanges 17, whereby there is provided means loosely connecting the lower end portions of the ribs to the support or bracket body 26.

The angularity adjusting means 30 for the ribs 15 of the mouldboard C, includes an elongated pivot member 31 projecting upwardly from and rigid with the central portion of the flange 27 to move therewith, and extending through the pivot opening 24, and being beneath the central of the ribs 15. Rigidly carried by an intermediate portion of the pivot member are a pair of bracket bodies 32, one of which is shown in Fig. 4, which project normal thereto in spaced-apart relationship and may be relatively short flat plates or rigid strips each having a longitudinally-extending slot 33 on one end portion thereof, with the size of the slot enlarged at intervals to form pin shank-receiving openings 34, 35 and 36 (three being shown, by way of example). At the other end portion of the bracket bodies is a pivot pin opening 37 for a pivot pin 38 which pivotally connects an actuator member 39 to the bracket bodies. The actuator member 39 comprises an elongated body portion 40 and an upwardly turned terminal portion 41 at each end, with these terminal portions constructed and arranged so that the outermost ribs 15 will rest upon the end faces 42. However, as the actuator member 39 is pivoted on the pivot pin 38, which extends through an opening 43 in the actuator body, offset from the center of the latter, one terminal portion will bear or press against one of these outermost ribs while the other terminal portion will move

away from the other outermost rib in order to twist or cant them.

Means 45 to adjustably limit the degree of such twisting or canting, employed in conjunction with the openings 34, 35 or 36, comprises an enlargement 46 of a part of the body portion 40 to provide a single elongated slot or opening 47 having side walls converging toward the pivot pin 38, and with the openings 34, 35 and 36 seen through the slot 47 when the longitudinal axes of the brackets 32 and elongated body portion 40 are parallel. Adapted to extend through the slot 47 and through any of the aligning openings 34, 35 or 36, is a removable pin 48 which is constructed to fit snugly in any of the openings 34, 35 or 36. It is obvious that, when the pin 48 is in the openings 34, the actuator member 39 cannot move independently of the bracket bodies 32, but when it is in the openings 35 the actuator member 39 will have some limited play in two directions, and when the pin 48 is in the openings 36, the actuator member will have additional play in two directions. In the first case, as the pivot member 31 is rotated, the bracket bodies 32 and actuator member will move in unison at all times while, in the second case, there will be a moderate warping of the ribs 15 but, in the third case, there will be a decided warping effect.

The construction of the angularity adjusting means 30 is such that there is a floating connection of the actuator member 39 with the outermost of the ribs 15 since the actuator member is not attached to them, but the outermost of the ribs normally rest upon the faces 42 of the actuator member and the ribs may turn or rock on their pivot pins 38 to a limited degree.

An additional support means D is provided for supporting the mouldboard C upon the plow frame A. Such may be a hook fixedly carried by the body portion 5 of the plow frame adjacent the upper end thereof, with the bill 50 of the hook adapted to enter a suitable eye or opening 51 in the longitudinal center of the free end part of the bracket body portion 21.

Means E to rock the plowshare C and, at the same time rock the plowshare C and cause canting or warping of the ribs 15, is shown as an elongated substantially L-shaped rod 55 having a handle 56 at its upper end, adjacent the handle 6, and rotatably extending, at its other or horizontal end 58 through the landside 7 to extend outwardly of the forward end thereof to support a bracket arm 57 fixed thereto which depends from and is rigid with the elongated bracket body 26 and depends from the center thereof.

From the above, it will be seen that the ribs 15 are associated so that the mouldboard may be quickly adjusted as a whole or the ribs warped or twisted in order to dispose parts of their body portions 16 diagonally with respect to the mouldboard as a whole. This, of course, will increase the areas between adjacent portions of the ribs and provide a somewhat shearing effect upon the soil, whereby the plow will be apt to travel more readily through the soil and the soil well pulverized. The specific

elongated opening 47 provides for some play, when the ribs are more definitely warped or twisted, so that they will not tend to break, as when an obstruction is encountered. The structures 32, 40 and 48 are disposed well inwardly of the outer edges of the mouldboard so that loosened soil will not be apt to clog the openings 34, 35, 36 and 47 nor dislodge the pin 48, yet the latter is readily accessible for manipulations thereof.

Various changes may be made to the shape, size and arrangement of parts without departing from the spirit of the invention or the scope of the following claims.

What is claimed is:

1. An adjustable mouldboard for a plough, comprising a plurality of spaced-apart inclined longitudinally twistable ribs, each having an outer face and upper and lower end portions with each face normally in substantially the same inclined plane; a rotatable support carried by said plough; means loosely connecting said lower end portions to said support; connecting means for rigidly interconnecting said ribs; and angularity adjusting means carried by said support to warp said ribs longitudinally so that portions of like faces thereof move out of said plane, including an elongated pivot member rigid with and extending from the center of said rotatable support to rotate therewith and rotatably carried by said connecting means, a bracket body carried by said pivot member and extending normal thereto and provided with a row of a plurality of spaced-apart pin-accommodating openings, an actuator member having portions in contact with the outermost of said ribs, pivot means pivoting said actuator member to said bracket body at a location at one side of the center of said actuator member, said actuator member having an elongated slot with opposite longitudinal walls thereof converging toward said pivot means, said elongated slot being at a location at the other side of the center of said actuator member and normally aligning with all of said openings, one of said openings normally opening at the narrowest part of said slot and the others of said openings being normally spaced from the planes of the converging longitudinal walls of said slot; and a removable pin snugly accommodated in one of said openings and extending into said slot and constructed and arranged to be inserted into any of said openings.

2. An adjustable mouldboard according to claim 1 characterized in that said portions of said actuator member are upturned-terminal portions with end faces in face contact with the under faces of said outermost of said ribs.

3. An adjustable mouldboard according to claim 1 characterized in that said row is a straight row extending longitudinally of said actuator member.

4. An adjustable mouldboard according to claim 1 characterized in that said bracket body and pin are confined to the intermediate portion of the under face of said mouldboard.
